UNITED STATES PATENT OFFICE.

ABRAM VAN BRUNT, OF WATERBURY, CONNECTICUT, ASSIGNOR TO WATERBURY
BUCKLE COMPANY, OF WATERBURY, CONNECTICUT, A CORPORATION.

SUSPENDER-BUCKLE.

1,186,623.

Specification of Letters Patent. Patented June 13, 1916.

Application filed September 3, 1914. Serial No. 860,060.

To all whom it may concern:

Be it known that I, ABRAM VAN BRUNT, a citizen of the United States, and resident of Waterbury, in the county of New Haven 5 and State of Connecticut, have invented certain new and useful Improvements in Suspender-Buckles, of which the following is a specification.

My invention relates to rustless suspender 10 buckles and particularly to that class of buckles shown and described in my prior United States Reissue Patent #13738 dated May 26, 1914.

The feature of the invention is to simplify and cheapen the construction of buckles of this class; to reduce the amount of stock required to form the buckle, and particularly to provide an intermediate bridge or support, toward and from which the 20 clamping bar of the locking-member is operated, to clamp the running portion of the webbing, through the operation of a lever member and the said locking member.

The invention further resides and consists 25 in the construction and novel combination and arrangement of parts hereinafter more fully described, illustrated in the accompanying drawings, and pointed out in the claims hereto appended.

Similar characters of reference denote 30 like or corresponding parts throughout the several figures of the accompanying drawings forming a part of this specification, and upon which,

Figure 1, shows a front view of my improved type of rustless buckle with webbing attached, the operating lever being in an open position. Fig. 2 is a side view of the buckle webbed and in a locked position. Fig. 3 is a central vertical sectional view of the 40 same buckle webbed, operating lever and locking member being open and the webbing in a relaxed position. Fig. 4 is a rear view of the buckle shown in the preceding figures, the webbing being omitted, and Fig. 5 is a similar rear view of a buckle made in accordance with my invention and illustrating a slightly modified form of frame member.

As will be noted the frame member 6 is 50 made of a single piece of wire, bent to form an upper longitudinal pivotal bar 7, straight parallel side portions 8—8 and lower horizontally arranged web attaching bars 9 and 10, said bars being preferably formed in two

sections and of the two end portions of the bars 9 and 10 of the frame wire and so arranged as to form two separate elongated eyes 11—11 whose inner ends are arranged adjacent to each other, to form a bridge 12 connecting the intermediate portions across from one bar or pair of bars to the other, and substantially midway of the length of the buckle and against which the clamping bar of the locking member operates. A lever 60 member 13 is hinged to the said upper longitudinal pivotal bar 7 of the frame member and has its free end extended forward so as to cover the front of the buckle when the lever is closed. A locking member 14 which is 65 also formed of wire is pivotally connected to the upper end portion of the lever member and eccentric to the pivotal connection of the said lever member with the frame member so that the webbing when threaded 70 through the loop 15 of the locking member will be clamped against the bridge portion 12 of the eyes and the upper and lower horizontal bars 9 and 10 of said eyes when the lever is closed. The end portions 16 of the 80 locking member are of an irregular shape to form the upper part of the rectangular loop longer across the top than the bottom, while the lower portion is narrower and deflected forward at an angle with relation 85 to said sides and so as to be projected through the eyes of the frame member as is clearly shown in the drawing.

The fastening end of the webbing 17 is passed over both bars of the eyes of the 90 frame and secured in any suitable way, while the running portion 18 of the said web is brought up and threaded through the loop of the locking member and forward of the said fastened end 16 of the 95 webbing. The running portion of the webbing is further passed from front to rear over the said attached end of the webbing and the lower bars of the frame-member and carried up under and to the rear of 100 the pivotal connections of the said frame and locking member with the lever-member, so as to cover all metal portions of the back of the buckle in a way to produce a rustless structure.

From the foregoing it will be apparent that when it is desired to adjust the running portion of the webbing, the lever-member would first be opened out to the portion shown in Fig. 3, which in turn 110

tends to shove the locking-member down and forward to free both the attached end of the webbing and the running portion. The webbing can thus be slipped up or 5 down through the frame and loop, whereupon it may again be secured by closing down the lever.

Having thus described my invention what I claim and desire to secure by Letters 10 Patent is:—

1. A rustless buckle comprising a frame-member having two horizontally aligned elongated loops formed in its lower end, a lever-member having its intermediate 15 part hinged to the upper part of the frame member, a locking member having a loop portion projecting through both the said loops of the frame member and including a horizontal gripping bar which acts 20 against the inner adjacent ends of the said loops of the frame, the upper portion of the said locking member being hinged to one end of the lever and eccentric to the pivotal connection of the said lever with the 25 frame member so that the webbing when threaded through the loop of the locking member will be pressed and clamped

against the inner ends of the said loops of the frame when the said lever is closed.

2. A rustless buckle comprising a frame-member having a pair of longitudinal bars at its lower end and a bridge connecting the intermediate portions of said bars forming eyes, a lever-member hinged to the upper portion of the said frame-member, a locking member having a loop portion operatively mounted between said bars and projecting through the eyes formed by the bars and including a horizontal gripping bar designed to grip the running portion of a 40 webbing against the bars of the frame and the bridge connecting the intermediate portion of said bars, the locking member being also hinged to the said lever and eccentric 45 thereof to the pivotal connection with the frame-member.

Signed at Bridgeport in the county of Fairfield and State of Connecticut this 24th day of Aug. A. D. 1914.

ABRAM VAN BRUNT.
